Term of patent 14 years

(Cl. D5—5)

Fig. 1

FIG. 4

Fig. 1 is a perspective view of a crib showing my new design wherein the scalloped panels are separated by narrow dividing stripes.

Fig. 2 is a fragmentary vertical section taken along the plane II-II of Fig. 1.

Fig. 3 is a perspective view of the crib design shown in Fig. 1 wherein the scalloped panels are abutting rather than spaced.

Fig. 4 is a fragmentary vertical section taken along lines IV-IV of Fig. 3.

This is a continuation-in-part of my application Serial No. D. 56431, entitled Crib, filed June 19, 1959, and Serial No. D. 56,432 entitled Crib, filed June 19, 1959.

The essential feature of my design resides in the portions shown in solid lines, and consists in an alternate arrangement of vertically scalloped, horizontally disposed panels overlying the end piece of a crib, substantially as shown.

I claim:

The ornamental design for a crib, substantially as shown and described.
